I⁷ Franklin Regan

UNITED STATES PATENT OFFICE.

LEVI R. COMSTOCK, OF MACON, MISSOURI.

STOVE-PIPE DRUM.

Specification forming part of Letters Patent No. **59,363**, dated November 6, 1866.

To all whom it may concern:

Be it known that I, LEVI R. COMSTOCK, of Macon city, county of Macon, and State of Missouri, have invented an Improved Revolving Flanged Spiral Radiator; and I do hereby declare the following to be an exact description thereof, reference being had to the accompanying drawings, and to the letters of reference marked thereon, making a part of this specification, in which—

Figure 1 represents a longitudinal section, and Fig. 2 a cross-section.

The nature of my invention consists in the construction of the spiral radiator having semicircular flanges on the inside of the cylinder, made of cast-iron or sheet-iron, and a center shaft, with flanges in sections set spirally on the shaft, with collars on the shaft, between which the ends of the cylinder are fitted and braced; also, pipes for receiving and discharging the heat, arranged and combined as hereinafter described, for the purpose of regulating the heat and saving the fuel.

A represents the cylinder, with its receiving-pipe B and discharge-pipe C, through which the heat passes, as indicated by the arrows. D is the shaft, upon which the flanged plates E are set spirally, or plates in sections, one section above another section, which give a

spiral current to the heat, so as to flow more in accordance with its usual spiral motion. Semicircular plates G are attached to the inside of the cylinder and between the plates E, so that by turning the shaft D, by the lever H, half round, the flow of the products of combustion can be made circuitous around and between the partitions E C; or, by turning the lever so as to bring those partitions on same side and parallel, a free passage for the smoke, &c., will be afforded on the other side. The lever H being permanently fastened to the shaft D, the collars J secure and brace the ends of the cylinder.

What I claim as my invention, and desire to secure by Letters Patent, is—

The spiral radiator having flanges G on the inside of the cylinder A, and a center shaft, D, with flanges E set spirally on the shaft, with collars J at the end of the cylinder, and pipes B and C, for receiving and discharging the heat, arranged, regulated, combined, and operated as herein described, and for the purposes set forth.

LEVI R. COMSTOCK.
